UNITED STATES PATENT OFFICE

112,238

DESIGN FOR A BRASSIÈRE

William Rosenthal, New York, N. Y., assignor to Maiden Form Brassiere Company, Inc., New York, N. Y., a corporation of New York

Application November 18, 1937, Serial No. 72,988

Term of patent 14 years

To all whom it may concern:

Be it known that I, William Rosenthal, a citizen of the United States, residing at 115 Central Park West, New York city, in the county of New York and State of New York, have invented a new, original, and ornamental Design for a Brassière, of which the following is a specification, reference being had to the accompanying drawing, forming part thereof.

In the drawing, it will be found that:

Fig. 1 is a front perspective view of a brassière, showing my new design; and

Fig. 2 is a rear perspective view of the brassière shown in Fig. 1.

The characteristic features of my design for a brassière are: the segmented breast pockets which are stitched, as shown; and, the center insert, separating the pockets in the front of the garment, and having triangular tabs stitched thereon, as shown.

I claim:

The ornamental design for a brassière, as shown and described.

WILLIAM ROSENTHAL.
